HUMIDIFYING APPARATUS

Frank A. Anetsberger and William Anetsberger,
Chicago, Ill.

Application January 19, 1931. Serial No. 509,566

3 Claims. (Cl. 126—350)

This invention relates to improvements in humidifying apparatus.

One object of the invention is to provide humidifying apparatus having a tank so mounted that it can be moved bodily by the weight of the water therein for operating a water supply valve and thus maintain the desired quantity of water in the tank.

Another object of the invention is to provide 10 humidifying apparatus having a tank which can be removed readily without the use of tools for the purpose of cleaning the tank or replacing or repairing the same. Other objects relate to various features of construction and arrangement of parts, which will be apparent from a consideration of the following specification and accompanying drawing, wherein:

Figure 1 is a longitudinal sectional view of 15 apparatus embodying the present improvements taken on line 1—1 of Figure 2.

Figure 2 is a top plan view of the apparatus, and

Figure 3 is a vertical sectional view taken on line 3—3 of Figure 2.

The apparatus, which in the form shown is 20 designed particularly for use in bakers' proof boxes, but which is not necessarily limited to such use, is provided with a base indicated generally by the numeral 10 having four lateral arms 11, 12, 13, and 14. A tank, indicated generally by the numeral 15, is provided having a well 16 and a longitudinally extending portion 17, as shown clearly in Figure 1. The tank 15 is provided with a perimetrical flange 18 having a depending portion 19. As shown in Figure 3, the flange 18 on the right hand side of the tank is at an elevation lower than the portion on the left hand side of the tank, while the end portions of the flange which connect the two side portions are disposed 25 at an angle as indicated by dotted lines in said Figure 1. The flange 18 with the depending portion 19 serves to entrap products of combustion and unconsumed gas and to conduct the same around the tank to the pipe 20 which is provided 30 with an enlargement 21, by means of which such gases are conducted from the proof box. The diameter of the enlargement 21 is sufficiently large to catch the gases escaping from the opening 18a during the slight to and fro movement 35 of the tank which takes place during the use of the apparatus.

The arm 12 of the base 10 may be provided with a groove 12a in its upper surface, as shown in Figure 1, within which is positioned a projection or flange 16a formed on the bottom of the

well 16. The arm 11 is provided with an adjustable stop 22 which limits the tilting of the tank 15 upon its pivot 16a in a counter-clockwise direction. The arm 14 has secured thereto a gas pipe 23 to the inner end of which is pivoted, as at 40 24, a gas burner 25. To the burner 25 is secured an operating arm 26 by means of which the burner 25 can be moved about the vertical pivot 24 to different positions under the tank 15, or it may be moved from beneath the tank as indicated by dotted lines in Figure 3. The gas pipe 23 is provided with a conventional valve 27.

A water pipe 28 is also secured to the arm 14 and is provided with a shut-off valve 29. The water flowing through pipe 28 passes through 45 the valve 29 and the upright pipe section 30, into a conventional sediment tank 31 and thence through pipe 32 out through a valve 33. Valve 33 has a needle 34 projecting from its free end, by means of which the flow of water through the 50 valve is controlled. The tank 15 is provided with a box-like housing 35 in which the pipe 32 projects and in which the valve 33 is positioned. A detachable cover 36 prevents the water from 55 splashing out of the housing when the valve is open. The bottom of the housing and also the cover are preferably provided with curved vertical fins 37 which direct the water through the open side of the box into the tank. The left hand end wall 38 of housing 35 is adapted to 60 press the needle 34 inwardly to close the valve when the tank 15 turns about its pivot 16a in clockwise direction.

When water in the tank has evaporated to the extent that the weight of that portion of the tank 65 at the left hand of the pivot 16a over-balances the remainder of the tank, it will move about its pivot in a counter-clockwise direction, thus moving the wall 38 away from the needle 34 whereby water will flow into the tank to replenish the diminished 70 supply. When sufficient water has flowed into the tank it will be over-balanced again due to the larger area of the right hand portion of the tank and the greater length thereof, and the tank will pivot in clockwise direction, thus pressing the needle 34 against its seat and cutting off the 75 supply. If the ratio of the capacity of the portion of the tank at the left of the pivotal axis to that at the right thereof is not such that the tank will tilt in one direction under the weight of a 80 predetermined minimum quantity of water to open the valve and in the opposite direction under a predetermined maximum quantity of water to close the valve, weights 39 may be secured to 85 the flange 18 at the left hand end of the tank, as 90 95 100 105 110

viewed in Figure 1, for effecting the tank action at the desired water levels.

The base 10 may be provided with vertical posts 40 and 41 to which the pipe 32 may be rigidly secured by means of clamps 40a and 41a respectively. The pipe sections 23 and 28 may be secured to the arm 14 by means of a plate 42 having at one end an extension 43 disposed beneath the handle 26. The flange 43 may have cast thereon legends such as "full steam", "half steam", and "dry heat". Thus when the arm 26 is over one of the legends the operator will know the position of the burner 25 without stooping to look under the tank. If the arm 26 is over the "full steam" legend, the operator will know that the burner 25 is approximately in the position shown in Figure 2, while if the arm is over the "half steam" legend he will know that the burner is slightly removed from beneath the tank although in such position that a small quantity of steam will be produced. When the arm 26 is over the "dry heat" legend the burner 25 is entirely removed from beneath the tank and serves to provide dry heat for the proof box, but not steam. As is shown in Figure 3, a baffle 43 serves to protect the tank 15 from the source of heat while the burner is in the dry heat position.

From the above it will be seen that a very compact humidifier has been provided in which a float controlled valve has been eliminated, which in the past has been the source of considerable difficulty in that water deposited material frequently caused the valves to clog and the tanks thus to burn out. It will also be apparent that the tank 15 can be removed for cleaning or replacement without the use of any tools since it merely rests upon the arm 12, being limited in its rocking movements by the stop 22 and the valve 33.

Although we have shown and described one embodiment of our invention for the purpose of illustration we do not wish to be restricted to the specific form shown nor to the particular use described, except as so limited by the appended claims.

What we claim is:

1. Humidifying apparatus comprising a support, a tank having a well adjacent one end thereof and being pivotally supported off center on

4 50

said support whereby said tank is tilted in one direction by a predetermined maximum quantity of water in said tank and in the opposite direction by a predetermined minimum quantity of water therein, a water supply conduit having a valve controlled by the movements of said tank for regulating the flow of water to said tank, a burner beneath said tank, said tank having a perimetrical flange provided with a continuous depending portion forming a passage for products of combustion, and a flue communicating with said passage.

2. Humidifying apparatus comprising a base, a tank positioned thereon, said tank having a perimetrical flange provided with a depending rim forming a passage around said tank for products of combustion, an exhaust flue communicating with said passage, a horizontally adjustable burner secured to said base, stops on said base for confining the movement of said burner between a position beneath said tank and a position beneath said flange at one side of said tank, a scale carried by said base, and a handle for said burner movable over said scale for indicating the position of said burner with respect to said tank.

3. Humidifying apparatus comprising a base having substantially parallel laterally extending arms, a tank pivotally supported off center on one of said arms, an adjustable burner beneath said tank resting on a second arm, said arm having stops for confining the movement of said burner between a position beneath said tank and a position at one side thereof, said tank having a water receiving chamber at one side thereof communicating with said tank, a water supply conduit extending into said chamber, a valve for said conduit, the ratio of the water holding capacity of the portions of said tank at each side of the pivotal axis being such that said tank is movable on said pivot in one direction by a predetermined quantity of water in said tank and in the opposite direction by a predetermined minimum quantity of water therein, said chamber being movable with said tank and having a portion for controlling said valve for regulating the flow of water to said tank.
